UNITED STATES PATENT OFFICE.

CORNELIS JOHANNES CRUIJFF AND SIMON BERNHARD VAN AALTEN, OF AMSTERDAM, NETHERLANDS.

CHECK FOR REVOLVING DOORS.

Application filed July 6, 1920. Serial No. 394,375.

To all whom it may concern:

Be it known that CORNELIS JOHANNES CRUIJFF, architect, a subject of the Queen of the Netherlands, and a citizen of the city 5 of Amsterdam, in the Kingdom of the Netherlands, residing at Fokke Simonszstraat 82-86, Amsterdam, Netherlands, and SIMON BERNHARD VAN AALTEN, merchant, a subject of the Queen of the Netherlands, 10 and a citizen of the city of Amsterdam, residing at Spuistraat 30, Amsterdam, Netherlands, have invented certain new and useful Improvements in Checks for Revolving Doors, of which the following is a specification.

This invention relates to checks for revolving doors comprising a middle wall and two wings at the ends thereof, said wings being curved like the segments of a circle, 20 the same being used with a door casing having similar segment-like walls. The object of said invention is to lessen the velocity of rotation and ensure that the door will always come to a stop position with the wings 25 inside of the corresponding parts of the door-casing. Heretofore such action has been imperfectly effected by means which allow some irregularity of resistance of the door to rotation and cause needless noise and 30 wear. To remedy these defects our invention consists in the devices and combinations hereinafter more particularly set forth and claimed.

On the accompanying drawing the invention is illustrated.

Fig. 1 is a vertical section through the apparatus in the position in which the pistons are in the middle of stroke and in which the door is in the position of rest.

Fig. 2 shows a horizontal section on the line A—B of Fig. 1.

Figs. 3 and 4 are sections through the cylinder in an enlarged scale on the lines C—D and E—F of Fig. 1 respectively.

Fig. 5 shows another construction of the means for stopping the door in the position of rest.

Figure 6 represents a longitudinal central sectional view similar to Figure 1 of the 50 modification shown in Fig. 5.

1 is the door-casing within which the door revolves on the shaft 2 provided with a crank 3. The connection-rod of said crank is connected with its free end by means of

a link to a vertical rod 5, which is fastened 55 at the bottom end to the piston-rod 6 and at the top end to a rod 7 slidably mounted in rings 8, which are fixed to the door-casing.

The piston-rod 6 carries the pistons 12, which move in a cylinder 11 fastened to the 60 door-casing. The cylinder 11 is closed at both ends and provided in the middle with an opening 19 for allowing a to and fro movement of the rod 5 and for the filling of the cylinder 11 with a suitable liquid as 65 for example oil. Further a canal 14 extending from one end to the other is provided in the piston-rod 6 and the pistons 12 and this canal 14 may wholly or partially be closed by means of an adjusting-screw 20 for the 70 purpose of regulating the resistance of the pistons against the rotation of the door.

Besides this the pistons 12 are provided with apertures 18, which can be shut off by means of valves 15, made of leather or similar material, and fastened to the pistons 12 by means of screws 17 (Fig. 3) and said valves are provided with openings 16 corresponding with the canal 14.

To both sides of the point of connection 80 with the rod 5 compression springs are arranged on the rod 7, said springs pressing at the one end against the rings 8 and at the other end against screw-nuts 10 arranged on the rod 7 and allowing the tension of the 85 said compression springs 9 to be regulated.

The working of the apparatus is the following:

When, after the cylinder 11 has been filled with a suitable liquid, for example 90 oil, and after adjustment of the screw 20 and screw-nuts 10, the door moves out of the position of rest and in the direction indicated on Figure 2 of the drawing by an arrow, then the right hand spring 9 will be compressed or weight 27 hereinafter described will be raised during the period that the door is passing through the first angle of 90 degrees, but as the door is moving during this period with a constant velocity of rotation, 95 the velocity of the pistons and thereby the resistance of same against the rotation of the door gradually decrease as the same approach the end of the stroke. During this movement of the pistons the liquid, for example oil, contained in the room within the cylinder 11 in front of the right hand piston 12 cannot escape through the openings 18

in said piston as the same are closed by the valve 15 being pressed against the front of said piston, and therefor this liquid is obliged to flow through the canal 14 into 5 the space contained within the cylinder 11 at the back of the left hand piston 12; further the liquid which may have reached the space within the cylinder 11 between the two pistons 12, for example by leakage, is 10 also allowed to reach the space within the cylinder 11 at the back of the left hand piston 12 and this to flow through the openings 18 in said left hand piston, which are uncovered as the valve 15 is standing apart 15 from the back of said piston.

After the door has passed through the first angle of 90 degrees and after the pressure of the public passing through has ceased, the door passes through the next 20 angle of 90 degrees in consequence of its own kinetic energy and in consequence of the expansion of the compressed spring 9 or tendency of the weight 27 to take a lower position. During this period the resistance 25 of the pistons against the rotation of the door gradually increases as said pistons approach the middle of the stroke and in consequence thereof the door will be brought to a stop in the position of rest, in which the wings 30 are inside of the segment-like walls of the door-casing.

As in this position of the door the pistons offer the greatest resistance against a rotation of the door and as the left hand 35 spring 9 is compressed or weight 27 is raised again as soon as the door has passed through the position of rest, the same will come to a stand-still without any oscillating.

Instead of the rod 7 and the compression 40 springs 9 the construction illustrated in Fig. 5 may be used. This construction, in which the connection-rod 4 of the crank 3 is fulcrumed and fixed with its fulcrumed end to the piston-rod 6, consists of a lever 25, 45 oscillating on a shaft 26, which is supported by girders 28 carried by the walls of the door-casing. The lever 25 is loaded at one end with a weight 27 and provided at the opposite end with a roller 24, pressed by 50 said weight to the bottom side of a disk 23 mounted on the shaft 2. Now the said bottom side of this disk is recessed and shaped in such manner that the weight takes the lowest position when the door is in the position of rest and is raised and takes the highest position when the door has passed through an angle of 90 degrees.

What we claim is:

1. An improvement in checks for revolving doors consisting in a pair of pistons moving in a cylinder and moved by the rotation of the door in such a manner that the

said pistons take the middle of the stroke when the door is in the position of rest.

2. An improvement in checks for revolving doors consisting in a pair of pistons moving in a cylinder and connected to the rotating shaft of the door by a connection-rod and a crank provided on said shaft, said pistons being mounted in such a way that 70 they take the middle of the stroke when the door is in the position of rest.

3. An improvement in checks for revolving doors consisting in a pair of pistons connected by a connection-rod to a crank 75 provided on the rotating shaft of the door and moving in a cylinder fixed to the door-casing in such a manner that the pistons take the middle of the stroke when the door is in the position of rest in combination with 80 means for bringing the door to a stop as soon as the same has reached the position of rest.

4. An improvement in checks for revolving doors consisting in a pair of pistons 85 connected by a connection-rod to a crank provided on the rotating shaft of the door and moving in a cylinder fixed to the door-casing in such a manner that the pistons take the middle of stroke when the door is 90 in the position of rest, in combination with compression springs arranged on a rod moving to and fro with the piston-rod in such a manner that one of the springs is compressed when the door is moved out of the position 95 of rest and is passing through the first angle of 90 degrees.

5. An improvement in checks for revolving doors consisting in a pair of pistons connected by a connection-rod to a crank 100 provided on the rotating shaft of the door and moving in a cylinder fixed to the door-casing in such a manner that the pistons take the middle of stroke when the door is in the position of rest in combination with a rocking lever supported by the door-casing and provided at one end with a weight and at the other end with a roller pressed by the weight against the bottom side of a disk 105 fixed on the rotating shaft of the door, said bottom side being shaped in such a manner that the weight takes the lowest position when the door is in the position of rest and is raised into the highest position when the door has passed through the first angle of 110 90 degrees.

In testimony whereof, we have signed our names to this specification in the presence of two subscribing witnesses.

CORNELIS JOHANNES CRUIJFF.
SIMON BERNHARD VAN AALTEN.
